SKELETON-LINED SHOE, WITH ATTACHING STRIP FOR ITS UPPER

Richard N. Sears, Woodstock, Conn., assignor to Bates Shoe Company, Webster, Mass., a corporation of Massachusetts

Application January 20, 1955, Serial No. 482,994

2 Claims. (Cl. 36—14)

The present invention relates to the art of shoemaking and, in particular, to a novel type of shoe construction, as will hereinafter appear. The shoe construction of the present invention not only permits a simple and economical method of manufacture, but also provides, from the standpoint of the wearer, a superior type of shoe construction.

The instant invention has particular utility in the construction of shoes which have soles and other parts made of rubber or the like material, especially cellular crepe rubber.

While cellular crepe rubber has heretofore been used in shoemaking by reason of its possessing certain desirable properties, its incorporation into shoes has presented various complications and difficulties, especially in the number of shoe parts required, and in the number of operations needed for their connection. The present invention, by reducing to a minimum the number of shoe parts, overcomes these difficulties, and in addition obtains advantages in the manufacturing procedure.

Therefore, it is a principal object of this invention to provide an improved shoe construction largely of cellular crepe rubber, as referred to above.

Other and further objects and advantageous features of the present invention will hereinafter more fully appear in connection with a detailed description of drawings, in which:

Fig. 1 is an exterior view in side elevation of the shoe, whose interior construction is the subject of this invention.

Fig. 2 is a bottom plan view of said shoe with a portion of the outsole broken away, to reveal certain features of interior construction.

Fig. 3 is a larger scale vertical sectional view, substantially on the line 3—3 of Fig. 1, showing one form of my invention.

Fig. 4 is a larger scale fragmentary sectional view with certain parts broken away, the section being taken along the line 4—4 of Fig. 3, looking in the direction of the arrows.

Fig. 5 is a view similar to Fig. 3 showing a slightly different form of my invention.

Fig. 6 is a larger scale fragmentary sectional view similar to Fig. 4, the section being taken along the section line 6—6 of Fig. 5.

Referring to the drawings, the shoe construction in both forms of my invention provides a suitable upper 1 and an insole 2 both composed of leather, or other suitable material, it being noted that the upper 1 terminates above the insole 2, as shown in Fig. 3 and also Fig. 5. In both forms of the invention, an outsole 4 is spaced below the insole 2, the intervening space in each instance receiving a filler 9 of appropriate thickness. The outsole 4 and filler 9 in each case, are preferably made of cellular rubber crepe.

For the purposes of the present disclosure, cellular rubber crepe may be considered as a gum or rubber-like material which is flexible but tough, springy, wear resistant and non-tacky under ordinary conditions of use.

2

Furthermore, cellular rubber crepe by reason of its natural permeability possesses the property of readily receiving and bonding with a suitable liquid adhesive, so that separate pieces thereof may be joined after application of the adhesive, by merely pressing the pieces together. This adhesive receptive property of cellular rubber crepe makes it readily and very strongly adherent, not only to other adhesive receptive materials such as fabric or webbing, but also to fabric or webbing which has been impregnated with rubber, as will hereinafter appear.

In the form of my invention shown by Figs. 3 and 4, the upper 1 is connected to the insole 2 by a shoe-encircling attaching strip 3a of relatively heavy fabric or webbing, said strip being bent to an approximately L-shaped cross-section so that its upper edge abuts the lower edge of the upper 1, while its lower portion extends for an appreciable distance beneath the insole 2. Said strip 3a, before its incorporation in the shoe, is preferably impregnated, as hereinafter described, with rubber. In this form of my invention, an additional slightly wider fabric strip 3b is cemented to the inner surface of attaching strip; this somewhat thinner fabric strip 3b, which provides in effect a skeleton lining, extends above and beyond the junction of attaching strip 3a and the upper 1.

The attaching strip 3a is connected to the upper 1 by stitching 5, which, as best shown in Fig. 4, extends in a zigzag manner between the abutted edge portions of the strip 3a and upper 1 respectively. The junction between the attaching strip 3a and upper 1 is strengthened by an external reinforcing strip 6, preferably composed of leather, which strip 6 is secured along its edges to the upper 1 and attaching strip 3a by conventional stitching 7 and 7'.

The external strip 6, besides strengthening the joint between the upper 1 and attaching strip 3a, so as to relieve the zigzag stitching 5 of strain, also adds to the appearance of the shoe, as will be evident from a consideration of Fig. 1. Furthermore, the projection of the strip 6 below the upper 1 enables the junction between the attaching strip 3a and the outsole 4 to be covered with a finish strip 8, as will be later described.

The upper edge of lining strip 3b is stitched to the upper 1 by means of conventional stitching 14 (Fig. 4) so as to reinforce the zigzag stitching 5 which joins the abutting edges of upper 1 and attaching strip 3a. The lower portion of the composite attaching and lining strip 3a, 3b is turned in under the edge of the insole 2 and secured to the under surface thereof by a layer of suitable adhesive, as indicated by the lines 10, 10 in Fig. 3. The insole 2 also has attached thereto by another layer of adhesive (see line 11, Fig. 3), the filler 9 of cellular rubber crepe, which occupies the space below the insole within the area defined by the turned-in portion of said composite strip 3a, 3b.

The outsole 4 is composed of cellular rubber crepe also and is attached to the shoe by applying to the exposed under surfaces of the attaching strip 3a and filler 9 another layer of adhesive (see line 12, Fig. 3), and then pressing the parts together.

The shoe is completed by attaching the finish strip 8 to the outer edge of the outsole 4 and to the exposed portion of the attaching strip 3a below the reinforcing strip 6. The finish strip 8 is also composed of cellular rubber crepe, and this strip is joined to the attaching strip 3a and the outsole 4 by applying to the parts another layer of adhesive (see lines 13, 13, Fig. 3), in advance of pressing the parts together. It is to be noted that when the finish strip 8 is thus incorporated in the complete shoe, the upper edge of the strip 8 fits snugly under the lower edge of the reinforcing strip 6.

The attaching strip 3a consists of a piece of cotton webbing which has received a first saturation of a natural crude rubber and a second saturation of a synthetic rubber that is basically paraacril, which is a mixture of neoprene and butadiene. The strip 3a is therefore impregnated with uncured rubber, both natural and synthetic. Now, when the skeleton lining 3b is cemented to the strip 3a certain curing agents in the cement will cure the rubbers contained in the attaching strip. These curing agents, which are of a dithiocarbamate nature, will not only cure the rubbers so as to produce a tough, flexible and resilient attaching strip as desired, but also will effect a very good bond between the attaching strip and the skeleton lining.

An attaching strip of fabric or webbing, such as the strip 3a of Figs. 3 and 4, by virtue of its internal fibrous nature, will not stretch appreciably while the shoe parts are being assembled; this means that the size of the shoe itself will not change (shrink) after it has been removed from the last.

Figs. 5 and 6 show a shoe construction which is practically identical with that of Figs. 3 and 4, except that here the inner or lining strip 3c, which overlaps upper 1, is rubber-impregnated, in the same fashion as the attaching strip 3a of Figs. 3 and 4. This rubber-impregnation of the inner or lining strip 3c enables it to be cemented firmly, as above described, to the attaching strip 3d, which, in this case, need not be rubber-impregnated. Furthermore, this rubber-impregnation of the inner or lining strip 3c enables it to be cemented more firmly, at 10, 10 to the leather insole 2, and also to the leather upper 1, where said strip 3c overlaps the lower edge of said upper. The lines of stitching 5, 7, 7 and 14 for Figs. 5 and 6 are the same as for the preceding figures, and the outsole 4 and finishing strip 8 are cemented in place exactly as described above for Figs. 3 and 4.

I claim:

1. In a shoe construction, a leather upper, a leather insole, the lower edge of said upper spaced above said insole, a first strip of rubber-impregnated fabric extending around said shoe for uniting said leather parts, said first strip at its upper edge inwardly laps the lower edge of said upper and stitched thereto, and at its lower portion bent inwardly beneath that insole, said lower portion adhesively connected to the under surface of said insole, a second strip of fabric adhesively connected to the outer surface of said first strip, the upper edge of said second strip abutting the lower edge of said upper and stitched thereto, the lower part of said second strip extending beneath said inwardly bent portion of said first strip and terminating at the inner edge of said first strip, a filler adhesively connected to the under surface of said insole within the area defined by the inner edges of said first and second strips, said filler equal in thickness to the combined thickness of said two strips, a platform outsole of cellular rubber crepe adhesively connected to the bottom surfaces of said filler and said second strip, and a finishing strip encircling said shoe and adhesively connected to the side edge of said outsole, the upper portion of said

finishing strip adhesively connected to said second strip above the latter's inwardly bent part.

2. In a shoe construction, a leather upper, a leather insole, the lower edge of said upper spaced above said insole, a fabric lining strip extending about said shoe and uniting said leather parts, said lining strip at its upper edge inwardly laps the lower edge of said upper and stitched thereto, and at its lower portion bent inwardly beneath said insole, said lower portion adhesively connected to the under surface of said insole, a fabric attaching strip extending about said shoe and adhesively connected to the outer surface of said lining strip, at least one of said two fabric strips rubber-impregnated, to increase the strength of said adhesive connection, the upper edge of said attaching strip abutting the lower edge of said upper and stitched thereto, and the lower part of said attaching strip extending beneath said inwardly bent portion of the lining strip and terminating at the inner edge thereof, a filler adhesively connected to the under surface of said insole within the area defined by the inner edges of said two fabric strips, said filler equal in thickness to the combined thickness of the two strips, a platform outsole of cellular rubber crepe adhesively connected to the bottom surfaces of said filler and said attaching strip, and a finishing strip encircling said shoe and adhesively connected to the side edge of said outsole, the upper portion of said finishing strip adhesively connected to said attaching strip above the latter's inwardly bent part.
